UNITED STATES PATENT OFFICE.

ELWYN G. HILL, OF PHILADELPHIA, PENNSYLVANIA.

CAR-FENDER.

1,151,684.

Specification of Letters Patent. Patented Aug. 31, 1915.

Application filed July 8, 1914. Serial No. 849,636.

To all whom it may concern:

Be it known that I, ELWYN G. HILL, a citizen of the United States, residing at Philadelphia, in the county of Philadelphia and State of Pennsylvania, have invented 5 certain new and useful Improvements in Car-Fenders, of which the following is a specification.

My invention relates to improvements in 10 car fenders, the object of the invention being to provide a pivoted scoop fender normally supported in an elevated position and caused to drop to operative position when an improved tripping fender contacts with 15 the person or object on the track, or when the same is caused to move by the action of a dog kicked by the motorman.

A further object is to provide an improved 20 mechanism of the character stated in which the movement of the tripping fender operates to apply the air brakes and open the electric circuit so as to insure the stopping of the car as well as the operation of the fender.

25 A further object is to provide improved means for holding the scoop fender in its lowered operative position, and provide improved means for raising the scoop fender to set position.

30 A further object is to improve upon the construction set forth in Patent No. 1,044,654 granted to me November 19, 1912.

With these and other objects in view, the 35 invention consists in certain novel features of construction and combinations and arrangements of parts as will be more fully hereinafter described and pointed out in the claims.

In the accompanying drawings: Figure 1 40 is a fragmentary view in side elevation illustrating my improved scoop fender in position to pick up a person or object on the track. Fig. 2 is a fragmentary view in transverse section on an enlarged scale on the line 2—2 of Fig. 1 showing the side frame in its inward position. Fig. 3 is a fragmentary plan view of the car platform illustrating the plunger for elevating the scoop fender and the dog to be operated by 45 the motorman's foot. Fig. 4 is an inverted plan view showing the scoop fender in its set position. Fig. 5 is a view in section on the staggered line 5—5 of Fig. 4. Fig. 6 is a view in transverse section on the staggered line 6—6 of Fig. 4. Fig. 7 is a fragmentary view in longitudinal section on the

line 7—7 of Fig. 4. Fig. 8 is a fragmentary view in longitudinal section on the line 8—8 of Fig. 4, and Fig. 9 is a fragmentary view in longitudinal section on the line 9—9 of Fig. 4.

1 represents the bottom of a car supporting a body 2, and at the forward end of the car, constituting a platform 3, as is common in the art. Brackets 4, 4 are secured to the 65 bottom 1 of the car in front of the wheels 5, and these brackets pivotally support my improved scoop fender 6. The scoop fender 6 comprises a main frame consisting of four transversely positioned tubular members 7, 70 8, 9, and 10, connected at their ends by angle bars 11 and covered by a netting 12^a.

The angle bars 11 are of general L-shape with the shorter member of the angle projecting upwardly.

75 Movable side sections 12 are provided on the scoop fender and consist of angle bars 13 corresponding in shape to the angle bars 11, and having rods 14 secured thereto. Four of these rods 14 project into the tubular members 7, 8, 9, and 10, and two of the rods 14 project through openings 15 in the angle bars 11, and are provided with enlargements 16 on their inner ends to limit the outward movement of the side frames. 80

85 The rods 14 in the tubular members 7, 9, and 10, bear against coiled springs 17, which exert a continuous outward pressure, tending to move the side frames outwardly and expand the scoop fender laterally. The rods 90 14 in the ends of the member 8 are connected to flexible devices 18, the latter being passed around pulleys 19 and out through a slot 20 in the rear wall of the tubular member. These flexible devices 18 connect to an operating cable 21 which is connected between 95 its ends to one member 22 of a bell-crank-lever 23. The cable 21 extends rearwardly from the bell-crank-lever 23 around the pulley 24, and thence forwardly to a drum 25 100 which has rotary mounting in brackets 26 secured to the bottom of the car platform 3, on which drum the cable is wound.

A curved arm 27 fixed to the scoop fender 6, extends rearwardly therefrom, and is positioned below and engaged by the member 28 of the bell-crank-lever 23, so that when the cable is wound upon the drum, it will exert a pull upon the side frames 12 to draw them inwardly, and will also swing the bell-crank-lever 23 on its fulcrum, the member 28 pressing downwardly upon the

curved arm 27, causing the scoop fender to elevate to its normal set position, as shown in Fig. 5. When the scoop fender falls, the 5 arm 27 will press the member 28 of the bell-crank-lever against the supporting bracket 29, and limit the downward movement of the fender.

The bell-crank-lever 23 is supported in a bracket 29 secured to the car bottom 1, and 10 the member 28 of said lever controls the operation of a wedge block 30 to lock the scoop fender in its lowered position, as will now be explained.

The block 30 is connected by a flexible 15 device 31 with the bell-crank-lever 23, said flexible device being passed over a pulley 32 above the block, and while I have illustrated a housing 33 to accommodate this pulley and block, it is to be understood that 20 any suitable mounting may be provided in accordance with the construction of the car.

The block 30 is movable against the front 25 face of one of the brackets 4, and is guided between flanges 34 on the bracket. The forward edge of the block engages one of the bars 11, and while said bar 11, at its 30 rear end, is at an incline when the scoop fender is in set position, as shown in Fig. 5, when the scoop fender falls or drops to operative position, this portion of the bar 11 is approximately parallel with the front 35 face of the bracket, so that the block 30 can fall into position and prevent any pivotal movement of the scoop fender. This position of parts is clearly shown in Fig. 1, where it will be noted that the block is so positioned that the scoop fender cannot rise, and hence the latter is held securely so as 40 to pick up a person or object and prevent the wheels from passing over the same.

When the drum 25 is turned to raise the scoop fender, it causes the bell-crank-lever 23 to operate, and through the medium of the flexible device 31, the block is elevated 45 to the position shown in Figs. 5 and 9. It is, of course, to be understood that when the scoop fender falls, the slack in the cable will permit the side frames 12 to spring outwardly, and that these side frames have 50 independent nettings 35 covering them, which nettings spread out as the frames move outwardly, and provide a support for a person or object.

36 represents a vertically movable plunger 55 which is movable in a sleeve 37 in the platform 8. This plunger 36 is provided with a rack 38 which engages a pinion 39 fixed to turn with the drum 25, so that the downward movement of the plunger compels the 60 drum 25 to turn in a direction to wind the cable 21 thereon. This plunger is operated by the downward pressure of the motor-man's foot, so that he can by this movement, raise the scoop fender to normal set position.

A tripping fender 40 is pivotally supported in brackets 41 secured to the car platform and located at the front of the platform in position to be struck by a person or object on the track. The tripping 70 fender 40, at its upper end, is provided with a shaft 42 extending into the brackets 41 and constituting the pivots of the tripping fender. On this shaft 42, a pinion 43 is secured and meshes with a rack 44 on a 75 plate 45. The plate 45 slides in guides 46 secured to the bottom of the car platform, and at its rear end is recessed, as shown at 47, to receive the plunger 36. The plunger 80 36 is provided in its front face with a recess 48 into which the plate 45 projects, and which holds the plunger in its lowered position.

The plate 45 is caused to move rearwardly by the downward and forward movement 85 of the tripping fender. In other words, the tripping fender tends always to swing downwardly by gravity to a vertical position, and hence when permitted, will force the plate 45 into locked engagement with 90 the plunger 36, hence when the plunger is forced downwardly to elevate the scoop fender 6, as soon as the plunger reaches a predetermined point, the plate 45 will spring into the recess 48 and hold the parts in set 95 position.

When a person or object is struck by the lower cross bar 49 of the tripping fender 40, said tripping fender will be caused to move rearwardly, and pinion 43 will move 100 the plate 45 forwardly out of the recess 48 and allow the scoop fender 6 to drop.

To insure a quick drop of the scoop fender 6, I provide a spring 50 which is coiled around the tubular member 9, and at one 105 end bears against the tubular member 10 of the scoop fender, and at its other end is connected to a bracket 4, although this spring may, of course, be otherwise mounted to assist gravity in moving the scoop fender 110 quickly to operative position.

51 represents an air pipe constituting a part of an ordinary air brake system having a valve 52 with a crank arm 53 secured to the stem of the valve, and connected by 115 a link 54 with the lower rod 49 of the tripping fender 40, so that when the tripping fender moves rearwardly it causes the valve to move and apply the brakes.

55 represents an electric switch arm connected by wires 56 with the electric motors of the car. The switch arm 55 is adapted to engage contacts 57 on a bracket 58 to which supply wires 59 are secured. A link 60 connects the switch arm 55 with the lower rod 125 49 of the tripping fender, so that when the tripping fender moves rearwardly, the switch arm 55 is caused to move in a direction to open the electric circuit and shut off the supply of current to the motors. It will 130

therefore be noted that when the tripping fender is operated, it not only causes the scoop fender 6 to drop in position to pick up a person or object, but it also causes the 5 brakes of the car to be applied and the supply of current to be shut off, thereby preventing accidents even though the motorman may fail to promptly do his duty.

On the platform 3 I provide a dog 61 secured to a shaft 62 projecting through the platform and having a finger 63 at its lower end in position to engage the rear edge of the plate 45. The motorman can kick this dog 61, which will compel the plate 45 to move forwardly out of the recess 48 of the plunger 36, and hence allow the scoop fender to drop before the tripping fender strikes a person or object. I hence provide two methods of operation, one under the 10 control of the motorman, and the other operated automatically by contact of the tripping fender with the person or object on the track.

Various slight changes might be made in 25 the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

35 1. The combination with a car, of a scoop fender pivotally supported on the bottom of the car, a drum mounted on the bottom of the car, a pinion secured to turn with the drum, a plunger movable through the car 40 platform and having a rack engaging the pinion, and a flexible device connecting the drum and the scoop fender, said flexible device being adapted to be wound on the drum to elevate the scoop fender, substantially as described.

45 2. The combination with a car, of a scoop fender pivotally supported on the bottom of the car, a drum mounted on the bottom of the car, a pinion secured to turn with the drum, a plunger movable through the car 50 platform and having a rack engaging the pinion, means engaging the plunger and adapted to hold the same in position to maintain the scoop fender elevated, and a tripping fender controlling the operation of said means, substantially as described.

55 3. The combination with a car, of a scoop fender pivotally supported on the bottom of the car, a drum mounted on the bottom of the car, a pinion secured to turn with the drum, a plunger movable through the car 60 platform and having a rack engaging the pinion, means engaging the plunger and adapted to hold the same in position to maintain the scoop fender elevated, and a

65 dog on the platform controlling the operation of said means, substantially as described.

4. The combination with a car, of a scoop fender pivotally connected to the bottom of the car, a drum on the bottom of the car having a pinion secured to turn therewith, a flexible device connecting the scoop fender and the drum, said flexible device being adapted to be wound on the drum to elevate 70 the scoop fender, a vertically movable plunger in the platform having a rack thereon engaging the pinion, a sliding plate adapted to engage a recess in the plunger to hold the plunger in its lowered position, and a 75 tripping fender controlling the movement of the plate, substantially as described.

5. The combination with a car, of a scoop fender pivotally connected to the bottom of the car, a drum on the bottom of the car 80 having a pinion secured to turn therewith, a flexible device connecting the scoop fender and the drum, said flexible device being adapted to be wound on the drum to elevate the scoop fender, a vertically movable plunger in the platform having a rack thereon 85 engaging the pinion, a sliding plate adapted to engage a recess in the plunger to hold the plunger in its lowered position, a pivoted tripping fender supported below the 90 platform, a pinion on the tripping fender, and a rack on the plate meshing with the pinion, substantially as described.

6. The combination with a car, of a scoop fender pivotally connected to the car, an 100 arm on the scoop fender, a bell-crank-lever pivotally supported on the bottom of the car and having one member engaging the arm for elevating the scoop fender when the bell-crank-lever is moved in one direction, a 105 drum on the bottom of the car, a flexible device connecting the bell-crank-lever and the drum, and means on the car platform for turning the drum, substantially as described.

7. The combination with a car, of a scoop fender pivotally connected to the car, an arm on the scoop fender, a bell-crank-lever pivotally supported on the bottom of the car and having one member engaging the 115 arm for elevating the scoop fender when the bell-crank-lever is moved in one direction, drum on the bottom of the car, a flexible device connecting the bell-crank-lever and the drum, means on the car platform for turning the drum, said scoop fender comprising a central main section and movable spring-pressed side sections, and flexible devices connecting the bell-crank-lever with the side sections holding said side sections 120 in their contracted position when the scoop fender is elevated, and permitting them to move outwardly when the scoop fender is lowered, substantially as described.

8. The combination with a car, of brack- 125

4
ets secured to the car, a scoop fender pivotally connected to the brackets, and a wedge block movable between the bracket and the scoop fender and adapted to fall 5 into position to hold the scoop fender against upward movement when the latter falls to operative position, substantially as described.

9. The combination with a car, of brackets secured to the bottom of the car, a scoop fender pivotally connected to the brackets, said scoop fender being composed of parallel transverse members, and bars connecting them, one of said bars having an upwardly 10 projecting arm, a block movable between the front edge of the bracket and said arm and adapted to fall by gravity into position to prevent the pivotal movement of the scoop fender when the latter falls to operative 15 position, substantially as described.

10. The combination with a car, of brackets secured to the bottom of the car, a scoop fender pivotally connected to the brackets, said scoop fender being composed of parallel 20 transverse members, and bars connecting them, one of said bars having an upwardly projecting arm, a block movable between the front edge of the bracket and said arm and adapted to fall by gravity into position 25

Copies of this patent may be obtained for five cents each, by addressing the "Commissioner of Patents, Washington, D. C."

to prevent the pivotal movement of the scoop fender when the latter falls to operative position, means for elevating the scoop fender, and a flexible device connecting the block with said means, whereby the block is moved upwardly when the scoop fender 35 is elevated, substantially as described.

11. The combination with a car, of brackets secured to the bottom of the car, a scoop fender pivotally supported in the bracket, a rearwardly projecting arm on the scoop fender, a bell-crank-lever having one member engaging the upper face of said arm, means manually operated to move the bell-crank-lever to force the arm downwardly 40 and elevate the scoop fender, means for releasing said scoop fender from locked position and permitting the same to fall, said arm being constructed to limit the downward movement of the scoop fender, substantially as described. 45

In testimony whereof I have signed my name to this specification in the presence of two subscribing witnesses.

ELWYN G. HILL.
